UNITED STATES PATENT OFFICE.

SIMEON C. KEITH, JR., OF NEWTON, AND ELEAZAR CATE, OF BELMONT, MASSACHUSETTS; SAID CATE ASSIGNOR TO L. E. KNOTT APPARATUS COMPANY, OF BOSTON, MASSACHUSETTS, A CORPORATION OF MASSACHUSETTS.

GUARD FOR BUBBLING DRINKING-FOUNTAINS.

1,111,540.

Specification of Letters Patent. Patented Sept. 22, 1914.

Application filed December 22, 1910. Serial No. 598,841.

To all whom it may concern:

Be it known that we, SIMEON C. KEITH, Jr., and ELEAZAR CATE, of Newton and Belmont, respectively, in the county of Middlesex and State of Massachusetts, have invented certain new and useful Improvements in Guards for Bubbling Drinking-Fountains, of which the following is a specification.

10 The object of the present invention is to provide an improved guard for bubbling drinking fountains. Guards of this character now in use are annular, and are arranged above the nozzle of the fountain 15 in a position to be engaged by the nose and chin of a person drinking. For sanitary reasons, a guard for this purpose should not be engaged by the nose, because if anything is deposited on the guard by the nose 20 of one person it will be communicated to some other person drinking afterward.

The essential feature of the present invention is the formation of the guard, by virtue of which it leaves a clear, unobstructed space for the nose of a person drinking and at the same time is adapted to be engaged by the chin and to thereby prevent the person's mouth from approaching too closely to the nozzle.

30 The invention embodies means by which the guard may be attached to the nozzle, said means adapting the guard to adjustment both longitudinally of the nozzle and circumferentially around the nozzle, so that it may be placed in any desired position.

Of the accompanying drawings which illustrate one form in which the invention may be embodied: Figure 1 represents a top plan view of a nozzle with the guard 40 attached. Fig. 2 represents a side elevation thereof. Fig. 3 represents a front elevation.

The same reference characters indicate the same parts wherever they occur.

45 The bubbling fountain for which this form of guard is especially adapted comprises a cylindric nozzle 10 to which the water is conducted by a pipe 11. The outlet of the nozzle is indicated at 12.

50 The guard is indicated at 13 and is supported by an arm 14, which in turn is supported by a nozzle-engaging member 15. The member 15 is formed to surround the

nozzle 10 and to be tightly engaged with the nozzle so as to be secured in various positions. The means illustrated for fastening the member 15 comprises a screw 16 connecting the two ends of the member 15 which are separated by a gap 17. The member 15 is therefore a split ring which may be contracted by the screw 16 so as to clamp the nozzle 10. By virtue of this construction the guard may be adjusted to various positions more or less distant with relation to the outlet, and may be otherwise adjusted circumferentially with relation to the nozzle.

It should be understood that the nozzle-engaging member may be varied in shape for nozzles of other than cylindric form, and the fastening means may likewise be varied to afford the aforesaid modes of adjustment of the guard without departing from the spirit of the invention.

By reference to Fig. 1, it will be seen that the guard is essentially U-shaped and that the ends 13' are separated sufficiently to leave a clear, unobstructed space so that there is no structure which might be engaged by the nose of a person standing at the position indicated by the arrow and facing in the direction indicated when the mouth of such person is in position for drinking at the fountain. The front portion of the guard may be engaged by the chin of the person drinking, this being sufficient to keep the person's mouth from approaching too closely to the nozzle. It is not necessary, however, that the guard 13 be U-shaped in order to be engaged by the chin and to leave an unobstructed space for the nose of the person drinking, the rearwardly turned ends 13' being unnecessary for this purpose but desirable for the purpose of guarding the nozzle against abuse.

We claim:

1. The combination with the nozzle of a bubbling drinking fountain, of a segmental guard therefor supported above the mouth of the nozzle so as to partly encircle the bubble issuing from the nozzle, the extremities of said guard being substantially diametrically opposite each other with reference to said bubble, said guard having a clamping portion arranged to clamp the peripheral surface of said nozzle to hold

said guard in various angular positions and at various levels.

2. An attachment for the nozzle of a bubbling drinking fountain, consisting of a
5 clamping device adapted to frictionally en-
gage the periphery of said nozzle to support
the device in various positions relatively to
said nozzle, a post extending upwardly
from said clamping device, and two arms
10 extending from said post in position to en-

gage the cheeks, near the corners of the
mouth, of a person drinking.

In testimony whereof we have affixed our
signatures, in presence of two witnesses.

SIMEON C. KEITH, JR.
ELEAZAR CATE.
